UNITED STATES PATENT OFFICE.

WILLIAM L. SILVEY, OF CASTLETON, INDIANA.

INDUCTION TELEGRAPH APPARATUS.

SPECIFICATION forming part of Letters Patent No. 244,082, dated July 12, 1881.

Application filed December 6, 1880. (Model.)

To all whom it may concern:

Be it known that I, WILLIAM L. SILVEY, a citizen of the United States, residing at Castleton, in the county of Marion and State of Indiana, have invented a new and useful Induction Telegraph Apparatus, of which the following is a specification.

My invention relates to a telegraph apparatus in which induced currents from an induction-coil are used to produce audible sounds; and the objects of my invention are, first, to provide a resounder operated by induction-currents, by means of which any signal given on a telegraph key-instrument at any one or 15 more places on the line is sounded audibly by the induction-resounder to any operator on the line; second, to provide an induction-resounder, and combine it with an induction-coil and a telegraph-key, by means of which the induced currents are employed for telegraphing. These objects I accomplish by the mechanism illustrated in the accompanying drawings, in which the entire device is represented by a single illustration.

Similar letters refer to similar parts throughout the several views.

A represents a table or board on which is secured an ordinary telegraph key-instrument, C C', and an ordinary induction-coil, B. The 30 primary wire *k* of the induction-coil B connects direct with the binding-screw *b*, and from thence to the ground through the wire *k'*. The primary wire *j* of the induction-coil B connects with the vibrating circuit-breaker G H, and by means of the adjusting-screw F', bracket F, and wire *i*, to the anvil-post E of the key-instrument C. The line-wire *l* is connected to the binding-screw *d* of the induction-coil, and the wire *n* is connected to the binding-screw 40 *e* of the coil, also to the binding-screw *g* of the resounder K.

The binding-screws *e d* of the induction-coil are provided with a switch, *x*, which connects the binding-screws when messages are received, but is disconnected when sending messages. When the binding-screws *e* and *d* of the coil are thus connected by the switch *x* the current of electricity, while passing through the resounder, produces a louder noise than 45 as if the current passed through the coil. The switch, when connected with the poles of the

coils also acts as a lightning-arrester, and prevents the coil from being burned out. The binding-screw *b*, to which the primary wire *k* and ground-wire *k'* are attached, is also connected with the battery by the wire *k''*, and is further provided with the wire *s*, which connects with the binding-screw *c*, which, in turn, is connected to the binding-screw *f* of the resounder, as shown.

The other battery-wire, *y*, is connected with the post D of the key C by the wire *h*, as shown. The binding-screws *b* and *c* are used for convenience, either one of which is sufficient, as they are connected together.

The resounder is formed of two parts, K K', and a cone-shaped sound-distributer, K'', united together, as shown, the distributer K'' being screwed fast in the upper part, K', and the parts K K' secured together in any ordinary manner.

The part K is provided with a circular chamber, K³, in its top, in which is firmly secured a metallic disk-plate, N, with a large hole, *p*, in its center. Immediately above this metallic disk N is placed a disk of paper, M, or other suitable material, to produce an intensified sound when acted upon by electricity.

The metallic button L is provided with a screw-threaded stem, P. This button rests on top of the disk M, and the stem P extends downward through a central hole in the part K, and forms a regulator, and is adjusted by the nut R. The nut R has a groove turned in it, and the plate S is inserted in the groove 85 formed in the nut. The plate S is made fast to the part K. Thus when the nut R is unscrewed the stem P and button L are raised off of the disk M, and when the nut is screwed up the button is drawn down onto the disk, 90 thus increasing or diminishing the sound transmitted to the disk by the electric current.

The binding-screw post *g* is connected with the stem P of the button L at *r* by the wire *o*. Thus the button L is connected directly to the 95 induction-coil B by the wire *o*, binding-screw post *g*, wire *n*, and binding-screw *e*. The binding-screw post *f* is connected with the metallic disk N, and by means of the wire *m*, binding-screw post *c*, wire *s*, screw-post *b*, and wire 100 *k'*, to the ground, and by the wire *k''* to the battery.

The operation of my new apparatus is as follows, the wires all being connected as described: When the key C of the instrument is depressed and connections made with the anvil-block on the post E a current of electricity is set up in the primary wires *j* and *k* of the induction-coil, which magnetizes the core of the coil, causing the circuit-breaker to vibrate, and each vibration toward the core 5 breaks the circuit. The current of electricity thus induced in the coil passes through the wire *n* to the stem P of the regulating-button L of the resounder, and passes through the disk M to the metallic disk N, thence off to the ground through the wires *s* *k'*. As the charges 10 of induced electricity pass through the disk M a very audible sound is produced, which is conveyed to the ear of the operator by means of the trumpet K², at the same time the charges 15 of induced electricity are carried from the other pole of the coil, through the line-wire *l*, to other stations on the line, when the induced current passes through another resounder in like manner and with like results.

20 It is obvious that this apparatus may be used 25 with or without a condenser.

What I claim as new, and desire to secure by Letters Patent, is—

1. In a telegraph apparatus in which induced currents of electricity from an induction-coil are used to produce audible sounds, the resounder composed of the parts K K', with trumpet K², the metallic disk N, the disk M, the regulator L P, with nut R, and the connections *n* *g* *o*, with an induction-coil, and 30 the connections *f* *m* and ground-wire *k'*, substantially as shown and described.

2. The combination, in a resounder, of the parts K K', the trumpet K², the metallic disk N, the disk M, the regulator L P, with adjusting-nut R, and the connections *o*, *g*, and *f*, 35 substantially as shown and described.

In testimony whereof I have signed my name to this specification in the presence of two subscribing witnesses.

WILLIAM L. SILVEY.
